US00D944726S

(12) **United States Design Patent** (10) **Patent No.:** **US D944,726 S**
(45) **Date of Patent:** **** Mar. 1, 2022**

(54) **CHARGING STATION**

(71) Applicant: **Parabit Systems, Inc.**, Roosevelt, NY (US)

(72) Inventors: **Mohammad Hasani**, Brooklyn, NY (US); **Robert J. Leiponis**, Glen Cove, NY (US)

(73) Assignee: **Parabit Systems, Inc.**, Roosevelt, NY (US)

(**) Term: **15 Years**

(21) Appl. No.: **29/716,221**

(22) Filed: **Dec. 7, 2019**

(51) **LOC (13) Cl.** **13-02**

(52) **U.S. Cl.**

USPC **D13/107**; D6/656

(58) **Field of Classification Search**

USPC D13/103, 106, 107, 108, 109, 110, 112, D13/116, 118, 119, 152, 184, 199; D6/329, 641, 647, 656, 698; D7/9.1, 9.2; D14/432, 433, 434; D15/9.1, 9.2

CPC H02J 7/0027; H02G 3/10; H05K 5/00

See application file for complete search history.

(57) **CLAIM**

The ornamental design for a charging station, as shown and described.

DESCRIPTION

FIG. 1 is a front, top, right perspective view of a charging station showing our new design;

FIG. 2 is top plan view thereof;

FIG. 3 is a bottom plan view thereof;

FIG. 4 is a right side elevational view thereof, the left side being a mirror image; and,

FIG. 5 is a front elevational view thereof, the rear view being a mirror image.

The broken lines in the drawings depict portions of the charging station that form no part of the claimed design.

1 Claim, 5 Drawing Sheets
